SIGN CONSTRUCTION

Application filed March 11, 1931. Serial No. 521,666.

Our invention relates to sign constructions and has particular reference to a sign construction in which a portion of the attractive feature of the sign constitutes its method of 5 illumination.

In producing attractive signs tubular lamps may be effectively employed for illuminating a portion of the sign, or its decorative ornamentation. Therefore it is an object of this invention to provide a construction 10 in which the appearance of the body of the sign is enhanced by decorative housing of a tubular source of illumination.

Another object of our invention is to provide 15 a sign construction in which a sign bearing the sign indicia is supported between a pair of tubular lamps provided with means for producing a decorative dividing of the illumination of the tubular lamps.

Our invention will be described with reference 20 to the accompanying drawing, wherein

Figure 1 is a front elevational view of a sign constructed in accordance with our invention; and

Figure 2 is a sectional view taken along line II-II of Fig. 1.

Referring to the drawing, we have illustrated 25 a sign construction in which a base 1 constitutes the support for a sign body 2 upon which suitable sign indicia 3 and 4 may be placed. The sign body 1 is illustrated as comprising a plate-like signboard of substantially rectangular configuration, though 30 it will be understood that any suitable configuration may be employed, to enhance the appearance of the sign.

Arranged along each of the side edges of 35 the sign body 2 is a tubular lamp 5 extending substantially parallel to the edges of the sign body. The tubular lamp 5 is illustrated as being enclosed in a tubular housing 6 which may be formed of metal or other 40 suitable material provided with a plurality of openings 7 therethrough to permit illumination from the lamp 5 to be visible through the enclosing tube 6.

The openings 7 may be of any suitable size 45 or shape and are preferably arranged in a

predetermined decorative design, such as is illustrated at 8, in Figure 1.

The upper end of the tubular housing 6 may terminate in a decorative end or knob 9 of any suitable design, this knob 9 having 55 formed therein or integral therewith a terminal 10 for engaging one end of the tube 5 to supply electric current thereto. If desired, the terminal 10 in each of the tubes 6 may be cross-connected at the upper end of the sign 60 by suitable conductors, not shown, so that the two lamps 5 may be placed in a single electric circuit.

The base 1 of the sign is illustrated as being 65 of substantially box like construction and may be employed to house a transformer 11 and other suitable controlling devices for furnishing the proper electric current to the tubular lamps 5. The enclosing tubular housing 6 may extend downwardly through this 70 box like base to be telescopically engaged by an upstanding lug 12 struck inwardly from the base of the box. A suitable electrical terminal 13 may be secured inside the tubular housing 6 and insulated therefrom, as is indicated at 14, to permit of ready electrical connection with the neon tube 5 with the 75 transformer 11 by means of conductor 15.

The sign construction illustrated and described herein produces an exceptionally 80 pleasing effect in that the illumination by a single lamp is so divided and projected through the decorative openings in the enclosing housing tubes 6 that various effects of 85 illumination may be obtained. Moreover, by enclosing the lamp 5 within the enclosing housing 6, the tubular lamp is protected against injury when the sign is arranged in such position as permits it to be touched or 90 contacted by persons viewing the sign.

By such enclosure of the lamps, injury to 95 persons who might inadvertently touch the lamps is avoided so that the sign construction illustrated is not only pleasing in appearance but increases the effective character of the sign by permitting its location in exposed positions where a non-enclosed lamp would not be permitted and in which the factor of safety both to the sign and to persons who 100 might touch the sign is increased.

While we have illustrated and described the preferred embodiment of our invention, we do not desire to be limited to any of the details shown or described herein, except as defined in the appended claims.

5 We claim:

1. In a sign construction, a relatively flat sign body, a base supporting said sign body, a pair of tubular lamps communicating with said base and extending along the borders of said sign body, a tubular enclosing housing for said lamp having perforations therethrough permitting illumination from said lamp to pass through said housing, and electric terminals formed in said base and in the remote ends of said housing for passing the electric current from said base to said lamps.

2. In a sign construction, a sign body, a box-like base for supporting said sign body, a pair of tubular housings extending from said base and bordering said sign body, the remote ends of said housings constituting electric terminals within said base, tubular lamps in each of said housings connecting with the terminals of said base and the terminal associated with said housing, said housing being provided with perforations permitting illumination of their said lamps to extend outwardly of said housing.

3. Signed at Los Angeles, California, this 2nd day of March, 1931.
